UNITED STATES PATENT OFFICE.

OSCAR J. ZIEGLER, OF FREEPORT, ILLINOIS, ASSIGNOR TO THE STOVER MANUFACTURING COMPANY, OF SAME PLACE.

GRINDING-MILL.

SPECIFICATION forming part of Letters Patent No. 634,053, dated October 3, 1899.

Application filed March 31, 1899. Serial No. 711,265. (No model.)

To all whom it may concern:

Be it known that I, OSCAR J. ZIEGLER, a citizen of the United States of America, residing at Freeport, in the county of Stephenson and State of Illinois, have invented certain new and useful Improvements in Grinding-Mills, of which the following is a specification.

My invention relates to improvements in mills of the class commonly known as "feed-grinders" and is fully described and claimed hereinafter.

Referring to the accompanying drawings, which form a part of this specification, Figure 1 is a central vertical section of a mill embodying my improvements. Fig. 2 is a like view of the same with some of the parts thereof in different positions from those shown in Fig. 1. Figs. 3 and 4 are detail views hereinafter fully described.

20 A is an annular chamber formed of two concentric rings A' A², connected at their bases by an outwardly-inclined bottom A³, preferably integral therewith and having vertical discharge-openings A⁴ therein, the outer ring A' being provided with internal gear-teeth A⁵, and the inner ring A² with an upwardly-projecting flange portion A⁶, for a purpose to be mentioned hereinafter.

25 B is a driving-ring provided with external gear-teeth B' and an annular concentric substantially parallel flange B² of less circumference than itself, an outwardly-projecting rim B³, and a spider B⁴, supporting a downwardly-extending tenon B⁵, adapted to enter 30 a part to be hereinafter described, the driving-ring B projecting downward into the annular chamber A and the annular flange B² thereof projecting downward inside of the ring A² of the chamber A.

35 C is a master-ring having vertical stub-axes C' and lugs C² projecting downward from the lower face thereof.

40 C³ are horizontal pinions mounted on the vertical stub-axes C' and meshing with the gear-teeth A⁵ B' on the outer ring A' of the chamber A and the driving-ring B.

45 C⁴ are antifriction-rollers mounted between the horizontal pinions C³ on bearings C⁵ in the lugs C² on the master-ring C, adapted to 50 traverse the circular bottom A³ of the chamber A and carry their master-ring C.

C⁶ are lugs to which a sweep (not shown) for rotating the master ring C may be attached.

D is an outside grinding-bur provided with a spider D', having a circular vertical opening D² in the apex thereof and rigidly connected with the annular chamber A. 55

E is an inside grinding-bur, the counterpart of the outside grinding-bur D, provided with a countersunk mortise E' in the upper central portion thereof to receive the tenon B⁵ on the spider B⁴. 60

F is a yoke resting upon the spider B⁴ of the driving-ring B.

G is a long bolt extending vertically through the parts E' B⁵ B⁴ F, whereinto it is secured by means of the lever-nut H. The bolt G suspends the inside grinding-bur E from the driving-ring B, and the lever-nut H serves to adjust the inside and outside grinding-burs E 70 D by drawing them into closer proximity, or vice versa.

The collar I and bolts and nuts I' I² secure the driving-ring B into engagement with the antifriction-rollers C⁴. 75

The purpose of the upwardly-projecting flange portion A⁶ on the inner ring A² and the downwardly-projecting flange B² on the driving-ring B is to prevent the grain being ground by the grinding-burs from escaping 80 between said flanges. Unavoidably, however, sometimes a small quantity of ground feed does escape between the flanges A² B². In that event it passes by the operation of gravity and by reason of the vibrations of the 85 running mill downward between the ring A² and driving-ring B onto the outwardly-inclined bottom A³ of the chamber A and outward through the vertical discharge-openings A⁴ therein. 90

The antifriction-rollers C⁴ render the mill light-running, and thus easy of operation, and the horizontal pinions C³ serve not only to communicate power from the master-ring C to the driving-ring B and thence to the inside 95 grinding-bur E, but they operate to speed them to a velocity double that of the master-ring C.

I claim—

1. In a grinding-mill, in combination, an 100 annular chamber formed of two concentric rings connected at their bases by an out-

ward-inclined bottom having vertical discharge-openings therein, the outer ring being provided with internal gear-teeth and the inner ring with an upwardly-projecting flange portion, a driving-ring, provided with external gear-teeth and an annular concentric flange, substantially parallel with and of less diameter than itself, the driving-ring projecting downward into the annular chamber and the annular concentric flange thereof projecting downward inside of the inner ring of the same, and the master-ring having horizontal pinions and antifriction-rollers mounted on bearings on the lower face thereof, the pinions meshing with the gear-teeth on the outer ring of the annular chamber and the driving-ring, and the antifriction-rollers being adapted to traverse the circular bottom of the annular chamber, substantially as and for the purpose specified.

2. In a grinding-mill, in combination, an annular chamber formed of two concentric rings connected at their bases by an outward-inclined bottom having vertical discharge-openings therein, the outer ring being provided with internal gear-teeth and the inner ring with an upwardly-projecting flange portion, a driving-ring, provided with external

gear-teeth and an annular concentric flange, substantially parallel with and of less diameter than itself, and a spider supporting a downwardly-extending tenon, the driving-ring projecting downward into the annular chamber and the annular concentric flange thereof projecting downward inside of the inner ring of the same, and the master-ring having horizontal pinions and antifriction-rollers mounted on bearings on the lower face thereof, the pinions meshing with the gear-teeth on the outer ring of the annular chamber and the driving-ring, and the antifriction-rollers being adapted to traverse the circular bottom of the annular chamber, an outside grinding-bur provided with a spider, having an opening in the apex thereof, and rigidly connected with the annular chamber, and an inside grinding-bur, provided with a countersunk mortise in the upper portion thereof to receive the tenon on the spider of the driving-ring, substantially as and for the purpose specified.

OSCAR J. ZIEGLER.
